UNITED STATES PATENT OFFICE.

GLENN W. TRAER AND CLAUDE M. GARLAND, OF CHICAGO, ILLINOIS, ASSIGNEES TO
UNIVERSAL COAL PRODUCTS COMPANY, OF CHICAGO, ILLINOIS, A CORPORATION
OF MAINE.

SYSTEM OF COOKING.

Application filed January 20, 1919. Serial No. 272,028.

To all whom it may concern:

Be it known that we, GLENN W. TRAER and CLAUDE M. GARLAND, citizens of the United States, and residents of Chicago, in the county of Cook and State of Illinois, have invented certain new and useful Improvements in Systems of Coking, of which the following is a description; reference being had to the accompanying drawings, which form a part of our specification.

Our invention relates more especially to a system of and apparatus for coking coal at comparatively low temperatures; the system comprising a retort wherein the volatile hydrocarbons may be distilled from the coal; more especially bituminous coal, at temperatures greatly less than are employed in the ordinary gas-house and by-product ovens for producing non-volatile coke.

The object of our invention is to provide a system comprising a series of retorts whereby the coking of bituminous coal, at comparatively low temperatures, may be effected in a substantially continuous manner, as distinguished from the usual intermittent method heretofore employed; the system including means whereby the coal will be maintained in the respective retorts in separate units, preferably of greater vertical dimensions than the transverse dimensions thereof; the heating of the coal units being accomplished as the respective coal units progressively travel from one end of the oven to the other through the respective retorts, heated to temperatures of such degree that a portion of the volatile hydrocarbon will be left in the product, namely those hydrocarbons which will not volatilize at the maximum degree of temperature proposed in the operation of our improved system; means whereby the coal is conveyed in separate units being divided into columnar sections or sub-units and composed of metal of great heat conductivity; while the means are adapted to travel freely through the coking retorts or chambers from end to end thereof.

Our invention contemplates an oven preferably provided with a plurality of retorts of length sufficient to receive a plurality of coal-holding means or containers just referred to, which are intended to be progressively moved at predetermined intervals through the distillation zone of the retorts,

from what may be termed the charging ends 55 toward the discharging ends thereof. The distilling or coking portions of the retorts are preferably formed of metallic shells secured together, end to end, and heated preferably by means of gas burners arranged in 60 flues disposed vertically on opposite sides of the retort proper; with the various flues communicating with a flue common to all of the heating flues. The various retorts, at fixed points, are all provided with take-off pipes for removing the distillate gases which rise in the retorts; said take-off pipes preferably communicating with the upper ends or tops of the respective retorts and the take-off pipes in turn conducting the 70 distillate gases to any suitable place of storage or scrubbing plant.

The system also comprises a series of retorts; both ends whereof are provided with portions separated from the main or heating 75 portion of the retort by closure means whereby locks are produced at both ends of each retort and the admission of air into the heating or distilling portions of the retorts will be substantially prevented; said portions or locks being of length sufficient to accommodate two of the coal-holding means or containers preferably with said portions divided into separate compartments by an inner closure means or gate disposed at a 85 distance from the outer closure means or gate sufficient to permit a unit or container to be disposed on both sides of the gate beyond the distilling zone.

The invention also contemplates means 90 adapted to compensate for the unequal expansion and contraction of the various parts of the oven so as to maintain a comparative gas and air-tight structure; and also means whereby the retorts may be alternately charged and discharged in successive pairs; the ends at the same side of the oven of a pair of retorts constituting a charging and a discharging end respectively.

The construction and operation of our improved system and its advantages will be more fully comprehended from the following detailed description of the accompanying drawings, wherein:

Figure 1 is a side elevation of a portion of our improved system, with an intermediate portion of the oven broken away and

100

105

other portions shown in section to show interior construction.

Figure 2 is a longitudinal diagrammatic section of one end of our improved oven.

5 Figure 3 is a similar view of the opposite end of the oven.

Figure 4 is a vertical sectional view taken at an intermediate point of the retort between the ends and sides thereof, namely at 10 a point through a pair of retorts and the correlated heating flues.

Figure 5 is a plan view of the intermediate portion shown in Figure 4, with parts broken away to more clearly disclose the internal construction.

Figure 6 is a vertical sectional view taken on the line 6—6 of Figure 4 looking in the direction of the arrows.

Figure 7 is a vertical sectional view taken 20 on the line 7—7 of Figure 4 looking in the direction of the arrows.

In the preferred embodiment of our invention as disclosed in the drawings, it comprises a horizontally disposed oven provided 25 with a plurality of preferably horizontally aligned retorts arranged in parallel relation with each other and extending lengthwise of the oven.

The oven is shown provided with a suitable foundation preferably comprising a plurality of columns or piers 20, of concrete or other suitable material, arranged in spaced relation as shown in Figures 1, 6 and 7, so as to provide suitable support at spaced 35 intervals apart for the respective retorts of the oven.

The spaces intermediate of the columns or piers 20, 20 are provided with transversely disposed flues, of suitable masonry, as shown 40 at 21 in Figures 1, 4, 6 and 7; and these flues all communicate with a common flue, not shown, for conveying the burnt gases or products from the respective transversely disposed flues 21 and also provide suitable 45 draft in the various heating flues superimposed on the transversely disposed flues 21 which are arranged on opposite sides of the various retorts of the oven.

The main portion of the oven is shown 50 constructed of suitable masonry, with the heating flues shown at 22 in Figures 4 and 7, formed of suitable refractory material. The flues 22 are arranged in series lengthwise of the oven, on both sides of the retort, as 55 shown in the diagrammatic plan views in Figures 2 and 3; with the flues extending vertically throughout the height of the retort 23, see Figure 4. The heating flues 22 preferably converge slightly toward the bottoms 60 and each communicates with a passage 24, all of which communicate with their respective transverse flues 21. The connections between the heating flues 22 and the passages 24 are preferably formed by means of telescopically arranged metallic members or ele-

ments shown in the nature of the metallic cylinder or open-ended casting 25, flanged at the upper end, as at 26, so as to be suitably supported by or embedded in the masonry of the oven, as shown in Figure 4; while the 70 lower end of the cylinder 25 extends into the metallic cup member 27 which is provided with the vertically disposed flanges arranged in spaced relation and adapted to contain sand or other suitable sealing material, as shown in Figure 4; the lower end of the element 25 extending into the sand or sealing material so as to provide an air-seal between the elements 25 and 27 and therefore for the connection between the heating- 80 flues and their respective transversely disposed flues 21 and at the same time compensate for any unequal expansion and contraction.

In order to provide suitable support for the refractory material of the heating flues 22, the metallic member 25 is shown provided with an internal flange or projection 28 on which the brick of the heating flues may rest and at the same time permit any differences in expansion or contraction. 90

The sides of the retorts 23 are preferably each formed of a series of metallic sections 29; the tops being formed of metallic sections 30, see Figures 4 and 6; while the bottoms of the retorts are formed of the metallic 95 channel members or sections 31. The bottoms of the retorts are supported by metallic caps or pedestals 32, which in turn are supported by the columns or piers 20. The respective metallic sections constituting the 100 sides, tops and bottoms of the retorts are all shown provided with outwardly disposed flanges, see Figures 4 and 6, which enable the respective sections to have close abutting relation with each other and to be bolted 105 together, as shown for example at 33 in Figure 6. The joints between the respective metallic sections, constituting the inner walls of the retorts, may be filled with any suitable substance adapted to provide gas-tight 110 joints throughout the lengths of the retorts. The side sections of the retorts are adapted to rest on ledges formed by the masonry of the heating flues, as shown in Figure 4; and the bottom sections 31 of the retorts 115 have their longitudinal sides preferably formed into the inverted U-shape, shown in Figure 4, thereby providing a suitable track or run-way for the wheeled coal carriers or containers 34; while the channels or intermediate portions of the bottom sections 31 are adapted to receive the steam-conduits 35 disposed lengthwise of the retorts and provided with a plurality of upwardly diverging jets or tips 36 whereby superheated 120 steam may be injected into the retorts at points centrally beneath the coal-carriers or containers 34. The steam conduits 35 of the respective retorts communicate with vertically disposed conduits 37 which extend into 125

130

the respective transversely disposed flues 21 and communicate with a main steam conduit 38. The support for the retorts on the columns or piers 20 is preferably formed by means of suitable roller-bearings shown at 39, which rest on and are adapted to move along the metallic pedestals or castings 32; the bottom castings 31 of the retort at points coincident with the bearings 39 being preferably provided with steel plates as at 40, see Figures 4 and 6, and thus permit longitudinal movement, due to expansion and contraction, of the retorts on the piers or columns 20.

15 The top of the oven at points coincident with the heating flues 22 is provided with gas-burner receiving openings 41, preferably arranged in pairs, as shown in Figure 5, so as to suitably heat the respective coal containing portions of the retorts intermediate of the ends thereof. The products of combustion are caused to pass downwardly through the heating flues 22 and therefore throughout the entire height of the retorts.

20 The lower portions of the retorts, as shown in Figure 4, are preferably made of somewhat greater lateral dimensions in order to accommodate the wheeled portions of the carriers or containers 34 which are disposed beyond the main sides of the carriers, as shown in Figure 4; and the retorts, at predetermined points, coincident with the positioning of the carriers in the retorts, are provided with suitable outlets or take-off pipes 42 for the purpose of conveying the distillates from the retorts to any suitable place of storage; the take-off pipes 42 of the various retorts connecting with a conduit or header common to all and shown at 43 in the drawings.

25 Each metallic section of the retorts is shown provided with a flange or rib disposed lengthwise of the section and preferably T-shape in cross-section, as shown at 44 in Figure 5; said ribs 44 providing a suitable bearing and interlocking point for the brick lining of the heating flues 22, namely the portion which extend transversely and separates one flue from the other, as shown at 22^a, see Figure 7.

30 The sides of the oven, namely at both ends of the retort, for a predetermined distance, are not provided with heating flues, see Figures 2 and 3, where the retorts are shown to continue and extend beyond the heating flues, to an extent slightly greater than the length of a pair of coal carriers which are shown at 34 and 34^a, thereby providing zones or locks at the ends of the retorts adapted to contain coal containers which, in the one instance, have not as yet been introduced into the coking or distillation zone of the retort and in the other instance carriers which have passed through the distillation zone and contain the coke.

These extended ends of the retorts are provided with inner doors, as at 45, see Figures 1, 2 and 3; which are suitably operated, as for example hydraulically, as contemplated in Figure 1, where double acting 70 water-cylinders are illustrated at 46, the pistons whereof connect with the inner doors 45 and cause the latter to be lifted into the casings 47 secured to suitable metallic frames in which the doors 45 slide. The 75 outer ends of the retorts are also provided with metallic doors 48 operated in any suitable manner, as for example by similar double acting water-cylinders 49 which cause the outer doors 48 to move upwardly into 80 the casings 50 when it is desired to open the doors. It is thus apparent that both ends of each retort are provided with what may be termed a lock, which enables the insertion of a coal container at the charging end and the withdrawal of a coke container or carrier at the discharging end, without admitting any substantial amount of air to the distillation zone or portions of the ovens; the inner and outer doors being 85 spaced apart a distance greater than the length of a container or carrier.

35 The containers or carriers, shown at 34, consist of suitable metallic receptacles or boxes of predetermined height, width and 90 length and open at the top; the containers or carriers being preferably of the type described in United States Letters Patent No. 1,267,479, of May 28, 1918. The containers are inserted into the retorts at suitable intervals of time at the charging ends thereof; each successive container forcing those which have preceded it until the distillation zones of the retorts have been filled as well as the zones just beyond the inner doors 100 at the charging ends. It is apparent, that after this has been accomplished, a further charging of the retorts will cause the first inserted container to be moved into the zone beyond the heating flues, at the 105 discharging end of the retort. In the operation of our improved system, in order to facilitate operation, each alternate retort will be charged at the one end of the oven, while the adjacent retorts will be charged at the opposite end of the oven; for example in Figures 2 and 3, the retort marked A will be charged at the left hand end in Figure 2, and discharge at the right hand end in Figure 3; while the adjacent retorts B and C will discharge at the left in Figure 2 and be charged at the right hand end, as shown in Figure 3. With this arrangement, the carriers or containers indicated at 34^a in retort A in Figure 2, and retorts 110 B and C in Figure 3, have not as yet passed into the distillation zone; while the carriers marked 34^b in retorts A, B and C in Figures 2 and 3, have passed through the distillation zone and therefore contain coke and are in 115

120 125 130 135 140 145 150 155 160 165 170 175 180

condition to be moved into the locks or zones intermediate of the inner and outer doors, as soon as the inner doors at said ends of the retorts are opened.

The system, as exemplified in the drawings, discloses suitable sub-structures at both sides of the oven, namely at opposite ends of the respective retorts, on which are mounted suitable rams, as shown at 51 and 52, which may be used for pushing and pulling, that is for pushing the coal filled containers into the retorts and for pulling the coke-holding containers out of the retorts;

15 coke-holding containers out of the retorts, the rams being operated by any suitable motive power and so mounted that they may be moved transversely of the ends of the retorts to enable them to be brought immediately opposite the respective ends of the various retorts of the oven.

The sub-structure, at the ends of the retorts, indicated at 53 in Figure 1, is provided with a platform, or carriage 54, on which the rams are mounted. The platforms 54 are adapted to move along the sub-structure 53 transversely of the retort-ends; such operation being induced by any suitable power 85

that by the time the container has passed through the lock, intermediate of the inner and outer doors, and has been withdrawn from said lock to the exterior of the retort, the contents will readily discharge therefrom upon unlocking the bottoms of the containers. The containers may then be recharged with coal and forced into the charging end of an adjacent retort. As will be understood from the operation, each container is progressively advanced through the heating or distillation zone of the retort before it reaches the non-heated portion of the retort in advance of its entry into the lock at the discharging end, so that each container remains in the heating or distillation zone a given predetermined length of time commensurate with the low temperature coking process to which our improved system is adapted.

The sub-structure 53 is shown provided with a suitable coke-receiving chute, as at 55, which may be provided with any suitable drag conveyor, as at 56, whereby the coke may be conveyed to a suitable coke cutter or place of storage.

The coal handling portion of the system comprises a super-structure consisting of any suitable framework, as shown at 57 in Figure 1, which is provided with belt or other suitable conveyors, not shown, whereby the coal which has been elevated or brought into the trough of the super-structure is conveyed into the suspended bunkers or hoppers 58, 58 arranged transversely of the retorts at both sides of the oven.

The bunkers or hoppers 58, at predetermined points throughout their lengths, are provided with discharge spouts as at 59, 11 rivetally suspended to the bottoms of the

In order to enable the containers to be forced out of the locks into the main portion of the retorts, that is beyond the inner doors after the latter are lifted, we prefer to provide the outer doors 48 with openings of size just sufficient for the passage of the rams 52; the openings being provided with sliding covers, or other suitable closing means, to permit movement of the container from the lock beyond the inner door after the latter has been raised without necessitating the opening of the outer door and thereby permitting ingress of air. In operation, it will be understood that after a container has been inserted into a lock at the charging end of the retort, the outer door is closed before the inner door is opened and the container is then forced beyond the inner door, after the latter has been raised, by inserting the ram 52 through the opening in the closed outer

door. During this operation, the inner door at the opposite end of said retort is opened, while the outer door at said end remains closed, thus permitting the container in proximity to the discharging end of the retort, to be forced, by the train of containers in the retort, into the lock intermediate of the inner and outer doors at the discharging end of said retort. This last mentioned container is then withdrawn from the lock at the discharging end of the retort after the inner door at said end has again been closed.

The sub-structure, at the ends of the retorts, indicated at 53 in Figure 1, is provided with a platform, or carriage 54, on which the rams are mounted. The platforms 54 are adapted to move along the sub-structure 53 transversely of the retort-ends; such operation being induced by any suitable power-driven mechanism in order that the carrier 34, which has been discharged from the retort, after having the coke discharged therefrom and having again been filled with coal, may be moved into alignment with an adjacent retort.

The sub-structure 53 is shown provided with a suitable coke-receiving chute, as at 55, which may be provided with any suitable drag conveyor, as at 56, whereby the coke may be conveyed to a suitable coke cutter or place of storage.

The coal handling portion of the system comprises a super-structure consisting of any suitable framework, as shown at 57 in Figure 1, which is provided with belt or other suitable conveyors, not shown, whereby the coal which has been elevated or brought into the trough of the super-structure is conveyed into the suspended bunkers or hoppers 58, 58 arranged transversely of the retorts at both sides of the oven.

The bunkers or hoppers 58, at predetermined points throughout their lengths, are provided with discharge spouts as at 59, pivotally suspended to the bottoms of the bunkers or hoppers at points where the latter are provided with discharge openings, as illustrated for example at 60 in Figure 1. The discharge spouts are preferably so pivoted that they may be swung to a certain extent from side to side and thus enable the coal to be charged into all portions or compartments of a container or carrier without necessitating movement of the carrier. The spouts are provided at their discharge ends with suitable closure means or valves as at 61, so that the discharge of coal through them may be controlled and shut off.

At points coincident with the discharge 125
spout 59, we prefer to provide means in the
nature of guards, as shown at 62, adapted to
fit the upper ends of the containers 34, to
guide the coal and prevent spilling thereof
during the charging process. The guards 130

62 are preferably made to conform with the cross-sectional configuration of the upper ends of the carriers 34 and are suitably suspended from the super-structure 57 by means of tie rods 63.

In our improved system, the retorts preferably consist of cast iron shells composed of a multiple of sections suitably secured together; with opposite ends of the retort-shells provided with inner and outer doors arranged in spaced relation a distance apart somewhat greater than the length of the carriers; and with the retort-shells also extended beyond the distillation or heating 10 zone of the retort, that is, beyond the point where the heating flues are located, so as to provide a zone or space at each end of all retorts, sufficient to receive at least a single container or carrier prior to the entry 15 of the container into the heating or distillation zone, at the charging end of the retort, or subsequent to its period in the heating or distillation zone and just prior to its entry into the lock intermediate of the inner and 20 outer doors at the discharge end of the retort. The cast iron shells which constitute the walls of the retorts are surrounded by layers of silica brick, or suitable refractory material, so that the flame from the 25 gas-burners in the heating flues will not come into immediate contact with the retort-shells; the metal portions of the oven and brick portions being so connected with one another as to compensate for differences in 30 expansion and contraction; while at the same time the cast iron oven-shells are yieldably or slidably supported on the various piers of the sub-structure, except possibly 35 to the center piers located intermediate of 40 the ends of the respective retorts, where the retort-shells are preferably securely bolted or otherwise secured to said piers.

In practice, the supporting piers are preferably so spaced as to provide suitable support, throughout the lengths of the retorts, at points apart substantially equal to the length of the containers, in order that a pier or support will be disposed approximately beneath every container when the 50 retorts have been completely charged.

The outer tops of the retorts are preferably formed of bricks which are supported or carried in a layer of sand or other suitable insulating material, as shown at 64 in 55 Figure 4.

In a low temperature system, the volume of volatile hydrocarbon distilled is materially less than is the case with other types of ovens or systems and therefore the flow or outward passage of the gases, by their own expansion, through the take-off conduits 42, would be comparatively slow, thus permitting the distillates to remain in the retorts for a greater period than desired, 60 with the result that the gases would be in 65

contact with the heated walls of the retorts as well as with the metallic containers, which would induce a cracking effect on the distillates. In order to overcome this undesired effect, I provide the superheated 70 steam conduits 35 centrally at the bottom of the retorts and beneath the containers, with the result that the rising steam induces a current to be set up in the retorts and therefore provides a medium whereby the 75 distillates are quickly carried off through the various conduits 42. Furthermore, with the superheated steam introduced centrally beneath the containers, it not only comes into direct contact with the bottoms of the 80 containers, but also with the side walls of the retort and sides of the containers, so that a direct conduction of heat to the metallic containers is had, without, however, affecting the hydrocarbons distilled from 85 the coal which is being coked in the retorts.

With the brick of the heating flues kerfed and dove-tailed with the vertically disposed ribs 44 of the retort-shells, as previously described, unequal expansion and contraction will be taken care of and expansion in the heating flues will be practically confined to the respective flues between the flanges 44; in other words, the tendency toward cumulative expansion throughout the 90 entire lengths of the heating flues will be substantially eliminated.

We have shown and described what we believe to be the simplest exemplification of our improved system, but alterations may 100 be made in certain details of construction, without, however, departing from the spirit of our invention.

What we claim is:—

1. In a system of the class described, an oven provided with a plurality of longitudinally disposed retorts composed of metallic sections secured together, the side members of said metallic sections being provided with vertically disposed ribs, heating flues arranged on both sides of the retorts and composed of refractory material, the heating flues being divided into independent sections with the refractory material of the heating flues arranged in interlocking relation with the vertically disposed ribs of the metallic sections so as to confine expansion and contraction to the respective flue sections, and a sub-structure for said oven provided with means whereby the retorts and heating flues are supported and expansion and contraction, independent of said sub-structure, permitted. 110 115 120

2. In a system of the class described, an oven having a plurality of retorts composed of metallic sections secured together, the side members of the sections being provided with outwardly disposed vertical ribs, and heating flues composed of refractory material arranged on both sides of each retort, 125 130

said heating flues being divided into a series of sections by means of transversely disposed refractory material, said refractory material having interlocking relation with the vertically disposed ribs of the retort sections whereby expansion and contraction is substantially confined to the respective sections.

3. In a system of the class described, the combination of a super-structure consisting of a plurality of longitudinally disposed retorts composed of metallic sections and a plurality of vertically disposed heating flues formed of refractory material disposed on both sides of the retorts, the refractory material of the heating flues being arranged in interlocking relation with the metallic sections of the retorts, with a sub-structure comprising a series of flues disposed transversely of the super-structure and in communication with the heating flues thereof, said sub-structure including a series of retort-supporting portions, air-sealing means intermediate of the sub-structure and the heating flues of the super-structure, and laterally movable means intermediate of the sub-structure and the retorts of the super-structure, said air-sealing means and laterally movable means permitting the retorts and the heating flues to have expansion and contraction independent of that of the sub-structure.

4. In a system of the character described, the combination of a super-structure having a plurality of retorts composed of metallic sections secured together and provided at both ends with inner and outer closure means, operable independently from the retort exterior and arranged in spaced relation to provide chambers therebetween, a plurality of heating flues, on both sides of the retorts, composed of refractory material arranged in interlocking relation with the metallic sections of the retorts at points intermediate of the ends thereof, with a sub-structure comprising a plurality of piers and flues common to all of the heating flues of the super-structure, telescopically arranged members intermediate of the sub-structure and the heating flues of the super-structure whereby said heating flues may have expansion and contraction independent of the sub-structure, said members being provided with an air-sealing medium, and laterally movable means disposed on the piers of the sub-structure for supporting the retorts of the super-structure and to permit expansion and contraction of said retorts.
